(57) **CLAIM**

The ornamental design for a ring for pump dispenser, as shown and described.

DESCRIPTION

FIG. 1 is a front, right side, top perspective view of a first embodiment of a ring for pump dispenser, showing our new design;

FIG. 2 is a front elevational view of the first embodiment thereof;

FIG. 3 is a rear elevational view of the first embodiment thereof;

FIG. 4 is a left side elevational view of the first embodiment thereof;

FIG. 5 is a right side elevational view of the first embodiment thereof;

FIG. 6 is a top plan view of the first embodiment thereof;

FIG. 7 is a bottom plan view of the first embodiment thereof;

FIG. 8 is a cross-sectional view of the first embodiment thereof, taken in the direction of line 8-8 of FIG. 6;

FIG. 9 is a side elevational view of the first embodiment thereof, shown in an exploded position of use with an exemplary pump dispenser; and

FIG. 10 is a side elevational view of the first embodiment thereof, shown in an assembled position of use with the exemplary pump dispenser.

FIG. 11 is a front, right side, top perspective view of the second embodiment of a ring for pump dispenser, showing our new design;

FIG. 12 is a front elevational view of the second embodiment thereof;

FIG. 13 is a rear elevational view of the second embodiment thereof;

FIG. 14 is a left side elevational view of the second embodiment thereof;

FIG. 15 is a right side elevational view of the second embodiment thereof;

FIG. 16 is a top plan view of the second embodiment thereof;

FIG. 17 is a bottom plan view of the second embodiment thereof;

FIG. 18 is a cross-sectional view of the second embodiment thereof, taken in the direction of line 18-18 of FIG. 16;

(Continued)

FIG. 19 is a side elevational view of the second embodiment thereof, shown in an exploded position of use with an exemplary pump dispenser; and,

FIG. 20 is a side elevational view of the second embodiment thereof, shown in an assembled position of use with the exemplary pump dispenser.

The broken lines are included for the purpose of illustrating the environmental structure and form no part of the claimed design.
